[57] CLAIM

The ornamental design for a chair, substantially as shown and described.

DESCRIPTION

FIG. 1 is a front elevational view of a chair embodying my new design;

FIG. 2 is a side elevational view thereof;

FIG. 3 is a top plan view thereof;

FIG. 4 is a rear elevational view thereof;

FIG. 5 is a front elevational view of another version of a chair embodying my new design;

FIG. 6 is a side elevational view thereof;

FIG. 7 is a top plan view thereof;

FIG. 8 is a rear elevational view thereof; and

FIGS. 9 and 10 are rear perspective views of the chairs shown in FIGS. 1-4 and 5-8, respectively.

The sides of the chair versions not shown in FIGS. 2 and 6 are mirror images of the sides shown, respectively.
